UNITED STATES PATENT OFFICE.

GEORGE HENRY WHEARY, OF RACINE, WISCONSIN.

DRAWER CONSTRUCTION FOR TRUNKS.

1,273,297.

Specification of Letters Patent.

Patented July 23, 1918.

Application filed February 28, 1916. Serial No. 80,857.

To all whom it may concern:

Be it known that I, GEORGE HENRY WHEARY, a citizen of the United States, and resident of Racine, in the county of Racine and State of Wisconsin, have invented new and useful Improvements in Drawer Construction for Trunks, of which the following is a description, reference being had to the accompanying drawings, which are a part of this specification.

My invention has relation to improvements in drawer construction for trunks.

In the class of trunks in which there is a compartment provided with a series of drawers (the so-called wardrobe trunks being an example) there have been provided a series of drawers so arranged that two drawers which are normally separate and distinct can be converted into a single large drawer to be utilized for ladies' hats, the drawers, when used in one form as ordinary trunk drawers, being capable of independent withdrawal for the purpose of gaining access to the contents thereof, whereas in the converted hat receptacle form being connected together to form a hat case of the size of both drawers combined and being capable of withdrawal together as one drawer.

Heretofore constructions have been provided for accomplishing the above end, and the present invention relates to an improvement over the means heretofore adopted, whereby simplicity and convenience in operation and economy in construction are the prime factors designed to be obtained.

With the above primary, and other incidental, objects in view, the invention consists of the device and parts or the equivalents thereof as hereinafter more fully set forth.

In the accompanying drawings:

Figure 1 is a front elevation of the drawer section of a wardrobe trunk, a fragment of the wardrobe section being shown in open position and by dotted lines;

Fig. 2 is a vertical sectional view of Fig. 1, on line 2—2 of Fig. 1;

Fig. 3 is an enlarged sectional view on the same plane as Fig. 2, but showing two of the drawers adjusted to form a single hat compartment;

Fig. 4 is a horizontal section on the line 4—4 of Fig. 1;

Fig. 5 is a horizontal section on the line 5—5 of Fig. 1;

Fig. 6 is a vertical section on the line 6—6 of Fig. 2;

Fig. 7 is a vertical central section of the drawer section of the trunk, showing a modified form of construction;

Fig. 8 is a similar vertical section of said modified form, on an enlarged scale and showing two of the drawers adjusted to form a single hat compartment; and,

Fig. 9 is a vertical sectional view of a modified form of drawer, with the upper front slidable cover shown in its lowermost position;

Fig. 10 is a similar view with the slidable cover in its uppermost position;

Fig. 11 is a transverse sectional view taken on line 11—11 of Fig. 10;

Fig. 12 is a vertical sectional view of another modified form of drawer construction;

Fig. 13 is a similar view with one of the drawers in inverted position;

Fig. 14 is a detail view of the locking means for holding the front side in adjusted position;

Fig. 15 is a similar view taken on line 15—15 of Fig. 14; and,

Fig. 16 is a sectional detail view of the guide means for holding the front slide.

Referring to the drawings, the numeral 9 indicates the drawer section of an ordinary wardrobe trunk, and 10 the wardrobe section thereof. The drawer section is formed with a compartment to receive the different drawers. A number of these drawers, designated by the numeral 11, are forms of drawers as ordinarily employed, whereas the drawers which are designated by the numerals 12 and 12' illustrate the two drawers which embody the improvements of my present invention. The two lower drawers 11 slide on ordinary angle-ways 13 while the lower drawer of the pair of convertible drawers is slidable in and out upon a partition 14. The upper member of the pair of convertible drawers also slides on angle-ways 13 and the very uppermost drawer 11 slides upon a partition 15.

The top of the drawer section has hinged thereto a lid or cover 16, shown in dotted lines, which, when the drawer section and wardrobe section are swung together is

adapted to cover the wardrobe section. This feature, however, forms no part of the present invention.

As shown most clearly in Fig. 2, the lower 5 drawer of the pair of convertible drawers is provided with a fixed front piece 17. Connected to the inner side of this fixed front piece, or cover, by a stud 18, is a spring arm 19, said spring arm carrying at its upper 10 end an outwardly projecting pin 20, which is adapted normally to extend through an opening 21 in said front piece 17.

In front of the fixed piece 17 is a sliding cover 22, said sliding cover provided on its 15 inner side with a vertically arranged metallic wear plate 23. When the sliding cover 22 is raised or lowered, the pin 20 rides along the plate 23, and thereby prevents direct contact of the pin 20 with the rear side 20 of the sliding cover 21. This, of course materially obviates and avoids wear.

At the lower edge of the fixed front or cover 17 of the lower drawer of the pair of convertible drawers, and projecting forwardly therefrom is a horizontal angle-strip 25 25. This strip projects forwardly sufficiently to form a seat for the lower edge of the sliding cover 22, said lower edge passing just back of the upstanding side flange of 30 the angle-piece.

Secured to the sides of the lower drawer 12 are vertical angle-pieces 25—25 which project forwardly a sufficient distance to permit the front flange thereof to overlap 35 the side edges of the slidable cover 22. There is also sufficient space between these front flanges and the fixed cover 17 to provide a guide-way for the slidable cover. These angle strips, just inwardly from the 40 corners thereof, are bulged outwardly, as indicated by the numeral 26, and extend outwardly so as to bear against the sides of the drawer section of the trunk and to prevent rattling and movement sidewise of the 45 drawers.

When the sliding cover 22 is in its lowered position as shown in Figs. 1 and 2, it is held releasably locked to the fixed or rigid front 17 by means of the pin 20, which pin not 50 only passes through the opening 21 in said fixed front piece, but also through a registering opening 27 in the sliding cover.

In the case of the top section of drawer 12' of the pair of convertible drawers, the 55 front cover 28 of said drawer instead of being fixed or rigid, is hinged, the hinge connection 29 being between the lower edge of said cover and the bottom of the drawer section. When the hinged cover is in its 60 normal upright closing position, it is releasably held in such position by means of a pivoted latch or dog 30, adapted to engage a notch 31 inside of the drawer section 12'.

The front or cover 28 being hinged at its 65 lower edge is, of course, capable of swinging

inwardly to the horizontal dotted line position, shown in Fig. 2. It is held in this horizontal position by any desirable means, such, for instance, as a pivoted angular catch 32, which catch is simply turned in 70 a direction to cause its upper horizontal arm to overlie the inner edge of said cover.

Beneath the lower edge of the pivoted cover 28, and secured to and projecting forwardly from the bottom of the drawer section 12' is a horizontal angular strip 33. Also secured to the sides of the drawer section and projecting forwardly from the sides are vertical angular guide-strips 34—34. These angular guide-strips in addition to performing the function of guides for the sliding cover 22, as hereinafter explained, also act as stops to limit the swing forwardly and outwardly of the hinged cover 28.

As will be seen from Fig. 2, the drawers 12 and 12' are shown in position for use separately or independently, and in this position are capable of being separately pushed inwardly or pulled outwardly.

Whenever it is desired to convert these two drawers 12 and 12' into a large single hat box or receptacle, the hinged cover 28 of drawer 12 is turned inwardly and downwardly to the dotted line position, shown in 95 Fig. 2, and held in such position by means of the catch 32. The drawer 12' is then inverted so that the bottom thereof, together with the hinged lid 28, occupy an uppermost position. In this inverted position, of course, the open top of the drawer is lowermost, so that there is no barrier between the upper drawer 12' and the lower drawer 12, and hence the two drawers form 100 a continuous large drawer capable of containing ladies' large hats.

Of course, if no means were provided to guard against it, the front of the upper drawer 12' would be open, when said drawer is thus inverted. The closure, however, is 105 provided for by reason of the employment of the sliding cover or gate 22. The handles of this cover are grasped, and the cover pulled upwardly thereby, the yielding character of the spring arm 19, permitting of 110 the disengagement of the pin 20 from the opening 27 of said cover. The cover, in its travel upwardly, is guided in the guide-ways formed by the lower angular strips 25—25 and the upper guide-strips 34—34. 115 The horizontal guide-strip 33, of course, does not interfere with the upward movement of the sliding cover 22, when the upper drawer is in its inverted position, inasmuch as said horizontal guide-strip 33, of course, under 120 such adjustment is at an upper position. When the cover or gate is raised to its full extent the upper edge thereof passes above the pin 20 and immediately the spring arm 19 springs outwardly and causes the pin to 125 130

engage beneath the lower edge of the cover 22, and thereby holds said cover in its raised position, as shown most clearly in Fig. 3.

Hat holders or forms 35 are provided 5 which are adapted to be snapped into holder members 36 of the lower drawer. One of the holder members is attached to the rigid or fixed cover 17 of the lower drawer, and the other holder member 36 is attached to 10 the rear wall of the lower drawer. When the hat holders 35 are snapped into engagement with holding members 36, the hat holders will extend above the lower edge of the inverted upper drawer, and prevent the 15 withdrawal of said upper drawer independently of the lower drawer. In other words, both drawers are then capable of being pulled out together.

Whenever it is desired to gain access to 20 the hat receptacle, the pin 20 is pushed inwardly to such an extent as to free it from engagement with the lower edge of the sliding cover 22. The cover is then free to slide downwardly to its position in front of 25 the fixed cover 17 of the lower drawer. Access is then readily obtainable to the lower drawer. It will be obvious that whenever it is desired to again form the two separate drawers all that is necessary is to disconnect 30 the top drawer 12' and turn the same to its original position, that is to say, to such position that its bottom is lowermost. This, of course, is done after the sliding cover 22 is lowered. When the drawer 12' is thus restored to its original position the catch 32 35 is turned so as to release the hinged cover 28. The said hinged cover is then turned upwardly and outwardly to its normal upright position, being held in such position 40 by the engagement of the catch 30 with the notch 31.

The construction, thus far described, contemplates two drawers 12 and 12', one (the lower) being of greater depth than the upper 45 drawer 12', and it will be seen that the sliding gate 22 is of such height that when raised to the position shown in Fig. 3, the lower edge will extend downwardly below the lower edge of the upper drawer 12', so 50 as to permit the pin 20 to extend beneath the lower edge of the sliding gate in order to support said gate in its raised position.

Figs. 7 and 8 show a modification wherein 55 the two drawers 12 and 12' are of equal depth. This form is desirable where it is desired to accommodate larger hats in the drawer sections. In this modified form, the sliding cover or gate 22 need not be extended so as to project at its lower edge, when it 60 is in raised position, below the upper edge of the drawer section 12, as is the case with the construction illustrated by Figs. 1 to 6, inclusive. In other words, the lower edge of the sliding cover 22, when said cover is in its 65 raised position, is flush with the lower edge

of the upper drawer section 12, so that the pin 20 engages beneath said lower edge when the cover is in raised position, and engages beneath the upper edge of the sliding cover, when said cover is in its lowered position. 70 This obviates the necessity of providing the hole 21 in the fixed cover 17 of the lower drawer section 12 and the hole 27 in the sliding cover. Also by this modification, when the drawers are converted, or are in 75 the position, shown in Fig. 8, to form the hat receptacle, and the hat forms 35 are removed, the drawer sections 12 and 12' are capable of being independently pulled outwardly and pushed inwardly. This is not 80 true of the sheet 1 form of construction, inasmuch as when the drawer sections are adjusted to form the hat receptacle, and the hat forms 35 are removed, it is impossible to pull outwardly the lower drawer section 12, 85 independently of the upper drawer section 12', in view of the fact that the upper section of the fixed cover 17 of the lower drawer section 12 is back of the downwardly projecting lower end of the sliding cover 22. 90

From the foregoing description of my invention, it will be seen that I provide a simple, convenient and easily manipulated drawer construction for converting two separate drawers into a large single hat receptacle, and by the particular construction of the present invention, I am enabled to dispense with the necessity of hinging the front cover of both of the drawer sections, and am enabled to make one front cover 100 fixed and immovable.

In the modified form shown in Figs. 9 and 10 and 11 the wear plate 23' is depressed outwardly to form a guide groove 37, as more clearly shown in Fig. 11, to accommodate the lock pin 20 and to permit said lock pin to extend farther outwardly to provide a more secure lock for holding the slide or cover 22 in its upper position. In order to provide for the automatic engagement of the 105 locking pin 20 with the lower edge of the locking cover when said slide cover is pushed upwardly, the portion 38 of the wear plate is inclined inwardly to swing the lock pin 110 inwardly and out of the groove and to permit it to snap beneath the lower edge of the said slide cover. As the end of the lock pin is rounded the slide may be unlocked from 115 its lower position by forcing upwardly on the slide and when in its upper position it 120 may be unlocked by pressing the locking pin inwardly.

In the modified form shown in Figs. 12, 13, 14, 15 and 16 the hinged front of the upper drawer 12' is eliminated and in lieu 125 thereof the slide cover 22' is adapted to serve as the front cover of said drawer in both positions of said drawer. In this construction the front slide is also guided by the angular guide strips 34, before mentioned, and 130

is locked to the drawer by a spring latch 39. The spring latch is formed with a rounded front end 40 so it will easily snap into and out of engagement with the apertured wear plate 41 mounted on the slide cover.

In using this last mentioned form of drawer when in inverted position, the drawer is pulled outwardly a slight distance so that the front slide will clear the front 10 of the lower drawer and when thus moved the front slide may then be pulled downwardly and disengaged from the drawer. This opening permits access to both drawers, but if desired both drawers may be removed 15 as before described.

When the upper drawer is not in inverted position the front slide forms a fixed cover for the front thereof.

From the foregoing description of my invention, it will be seen that I provide a 20 simple, convenient and easily manipulated drawer construction for converting two separate drawers into a large single hat receptacle, and by the particular construction of the present invention, I am enabled to dispense with the necessity of hinging the front cover of both of the drawer sections, and am enabled to make one front cover fixed 25 and immovable.

I have also shown and described my improvements in connection with trunks and particularly in connection with wardrobe trunks, yet I do not wish to be understood 30 as limiting myself thereto, as it will be obvious that the invention is applicable to drawer construction, generally.

What I claim is:

1. A drawer construction for trunks and the like having a compartment, comprising 40 drawers positioned in said compartment, one of the drawers having an open front portion, and the other drawer having a closed front portion, and a slidable cover for the open front portion movable to a position to be carried by the drawer with the closed 45 front portion.

2. A drawer construction for trunks and the like having an open front drawer compartment, comprising drawers positioned in 50 said compartment, one of said drawers having an open front portion and the other drawer having a closed front portion, the drawer having the open front portion being movable to a position to combine its space 55 with the space of the other drawer into one compartment, and a slidable cover for the drawer having the open front portion movable to a position to be carried by the drawer with the closed front portion.

60 3. A drawer construction for trunks and the like having a drawer compartment, comprising drawers positioned within said compartment, one of the drawers having an open front portion, and the other drawer 65 having a closed front portion, and a slid- 60

cover, said cover, under one slidable adjustment thereof, being moved to a position to be carried by the drawer having a closed front portion, and, under the other slidable adjustment thereof, being moved to a position to close the open front portion of the other drawer.

4. A drawer construction for trunks and the like having a drawer compartment comprising drawers positioned within said compartment, one of the drawers having an open front portion, and the other drawer having a closed front portion, a slidable cover, said cover, under one slidable adjustment thereof, being moved to a position to 75 be carried by the drawer having a closed front portion, and, under the other slidable adjustment thereof, being moved to a position to close the open front portion of the other drawer, and means for releasably locking the slidable cover in its raised position.

5. A drawer construction for trunks and the like having drawer compartments comprising drawers positioned within said compartments, one of the drawers having an open front portion, and the other drawer having a closed front portion, a slidable cover, said cover, under one slidable adjustment thereof, being moved to a position to 90 be carried by the drawer having a closed front portion, and, under the other slidable adjustment thereof, being moved to a position to close the open front portion of the other drawer, and means for releasably locking the slidable cover in its raised and lowered positions.

6. A drawer construction for trunks and the like having an open front drawer compartment comprising drawers positioned in 105 said compartment, one of the drawers having an open front side, and the other drawer having a closed front portion, the open front drawer being movable to a position to combine its space with the space of the other drawer into one compartment, a slid- 110 able cover, said cover, under one slidable adjustment thereof, being moved to a position to be carried by the drawer having a closed front portion, and, under the other slidable adjustment thereof, being moved to a position to close the open front portion of the other drawer, and vertical guide-ways in which the slidable cover is movable.

7. A drawer construction for trunks and the like having a drawer compartment comprising drawers positioned within said compartment, one of the drawers having an open front portion and the other drawer having a closed front portion, vertically-disposed angle-strips secured to the opposite sides of the two drawers and projecting outwardly therefrom, the front members of the angle-strips projecting inwardly toward each other, and spaced a distance from the 120 125 130

front of the drawers to form guide-ways, and a cover slidable in the guide-ways, said cover, under one adjustment thereof, being movable to a position to be carried by the 5 drawer having the closed front portion, and under the other adjustment thereof, being moved to a position to close the open front portion of the other drawer.

8. A drawer construction for trunks and 10 the like having a drawer compartment comprising drawers positioned within said compartment, one of the drawers having an open front portion, and the other drawer having a closed front portion, a slidable cover, said 15 cover, under one adjustment thereof, being moved to a position to be carried by the drawer having the closed front portion, and under the other adjustment thereof, being moved to a position to close the open front 20 end of the other drawer, and automatic means adapted, when the sliding cover is raised to a position to close the front of the drawer having an open front, to automatically and releasably lock the said sliding 25 cover in its raised position.

9. A drawer construction for trunks and the like having a drawer compartment, comprising drawers positioned within said compartment, one of the drawers having an open 30 front portion and the other drawer having a closed front portion, a slidable cover, said cover, under one adjustment thereof, being moved to a position to be carried by the drawer having the closed front portion, and, 35 under the other adjustment thereof, being moved to a position to close the open front end of the other drawer, and means adapted, when the sliding cover is raised to a position to close the front of the drawer having an 40 open front, to automatically and releasably lock the said sliding cover in its raised position, and, when said sliding cover is lowered to its full extent, to automatically and releasably lock the sliding cover in its low- 45 ered position.

10. A drawer construction for trunks and the like having a drawer compartment comprising drawers positioned within said compartment, one of the drawers having an 50 open front portion, and the other drawer having a closed front portion, a slidable cover, said cover, under one adjustment thereof, being moved to a position to be carried by the drawer having a closed front portion, and, under the other adjustment thereof, being moved to a position to close the open front end of the other drawer, and a spring arm provided with a projecting pin, said pin adapted, when the sliding cover is 55 moved to its closing upper position, to automatically engage said sliding cover to releasably hold it in its closing position.

11. A drawer construction for trunks and the like having a drawer compartment, comprising drawers positioned within said com- 60

partment, one of the drawers having a slid- 70 able cover, said cover, under one adjustment thereof, being moved to a position to be carried by a drawer having a closed front portion, and under the other adjustment thereof, being moved to a position to close the open front end of the other drawer, a spring 75 arm connected to the lower drawer and provided with a projecting pin, said pin adapt- 80 ed, when the sliding cover is moved to its closing upper position, to automatically engage said cover to releasably hold it in its closing position and said pin adapted, when the sliding cover is moved to its normal lowered position, to automatically engage the sliding cover to releasably hold said cover in its lowered position.

12. A drawer construction for trunks and the like having a drawer compartment, comprising drawers positioned within said com- 85 partment, one of the drawers having an open front side, and a cover therefor, said cover hinged at its lower edge and adapted to be turned downwardly to a position against the bottom of the drawer, with a means for 90 releasably locking said hinged cover in the latter position, and the other drawer having a closed front side, the drawer with the open front side being invertible so as to bring its bottom piece and the hinged cover 95 adjusted thereagainst to an uppermost position whereby the spaces of the two drawers are combined into one compartment, and a slidable cover movable to a position to be carried by the drawer with the closed front 100 portion, and also movable to a position to close the open front side of the other drawer, when said latter drawer is in inverted position.

13. A drawer construction for trunks and the like having a drawer compartment, drawers positioned within said compartment, one of the drawers having an open front portion, and the other drawer having a closed front portion, the closed front portion provided with an aperture, a slidable cover provided with an aperture, said cover, under one slidable adjustment thereof, being moved to a position to be carried by the drawer having the closed front portion, at 110 which position the aperture thereof is in register with the aperture of the closed front portion, and, under the other slid- 115 able adjustment thereof, the said cover being moved to a position to close the open front side of the other drawer, and a spring arm carried by the lower drawer of the pair, said spring arm having a projecting pin which is adapted, when the sliding cover is lowered to engage the registering aper- 120 tures in the fixed cover and sliding cover and when the sliding cover is raised to en- 125 gage beneath the lower edge of said cover and thereby hold the same in its raised position.

14. A drawer construction for trunks and the like having a drawer compartment comprising drawers positioned within said compartment, one of the drawers having an open front side, a slideable cover, said cover, under one adjustment thereof, being moved to a position to be carried by the drawer having a closed front portion, and, under the other slideable adjustment thereof, being moved to 5 a position to close the open front portion of the other drawer, vertical outstanding angle-pieces along the side edges of the drawers forming guide-ways in which the slideable cover moves, and a horizontal outstanding 10 angle-piece along the lower edge of the lower drawer, and having a seat for the slideable cover, when said cover is moved to its lowermost position.
15. A drawer construction for trunks and the like having a drawer compartment, comprising drawers positioned in said compartment, one of said drawers having an open front and adapted to be positioned to 15 combine its space with the space of the other drawer into one compartment, and a cover for said open front drawer slideable to a position to permit access to the combined compartment.
16. A drawer construction for trunks and the like having an open front drawer compartment, comprising drawers positioned in said compartment, one of said drawers having an open front and adapted to be positioned to 20 combine its space with the space of the other drawer into one compartment, and a slideable cover for said open front drawer movable to a position to permit access to the combined compartment.
17. A drawer construction for trunks and the like having an open front drawer compartment, comprising drawers positioned within said compartment, one of the drawers having an open front side, a slideable cover, said cover, under one adjustment thereof, being moved to a position to be carried by the drawer having a closed front portion, and, under the other slideable adjustment thereof, being moved to 25 a position to close the open front portion of the other drawer, vertical outstanding angle-pieces along the side edges of the drawers forming guide-ways in which the slideable cover moves, and a horizontal outstanding angle-piece along the lower edge of the lower drawer, and having a seat for the slideable cover, when said cover is moved to its lowermost position.
18. A drawer construction for trunks and the like having an open front drawer compartment, comprising two drawers positioned one above the other in said compartment, the upper drawer having an open front and adapted to be positioned to 30 combine its space with the space of the lower drawer into one compartment, and a slideable cover for said open front drawer removable downwardly while the two drawers are combined to permit access to the combined compartment.
19. A drawer construction for trunks and the like having an open front drawer compartment, comprising two drawers positioned one above the other in said compartment, the upper drawer having an open front and being invertible to combine its 35 space with the space of the lower drawer into one compartment, and a slideable cover for the front of the upper drawer movable downwardly in front of the lower drawer to permit access to the combined space of both drawers.
20. In testimony whereof, I affix my signature.

GEORGE HENRY WHEARY.
